UNITED STATES PATENT OFFICE

131,201

DESIGN FOR A COMBINED RADIO AND BEDSIDE TABLE

Ervin H. Thompson, New York, N. Y.

Application May 8, 1941, Serial No. 160,840

Term of patent 7 years

all whom it may concern:

Be it known that I, Ervin H. Thompson, a citizen of the United States, residing at New York, in the county of New York and State of New York, have invented a new, original, and ornamental Design for a Combined Radio and Bedside Table, of which the following is a specification, reference being had to the accompanying drawing, forming part thereof, wherein:

Fig. 1 is a perspective view taken from the left front of a combined radio and bedside table embodying my new design, the drawer and door being closed;

Fig. 2 is a similar perspective view, with the door opened to expose a radio apparatus to view and with the drawer partly drawn out to the left;

Fig. 3 is a top plan view of the table with the door open and the drawer partly drawn out to the right; and

Fig. 4 is a front elevation of the table with the parts in the position shown in Fig. 3. The rear of the table is substantially plane.

A portion of the legs are broken away in Figs. 2 and 4 for convenience of illustration.

The characteristic features of my design are shown in full lines.

I claim:

The ornamental design for a combined radio and bedside table, substantially as shown and described.

ERVIN H. THOMPSON.
